UNITED STATES PATENT OFFICE.

ARCHILLES A. BARTON, OF LOS ANGELES, CALIFORNIA.

PUMP PISTON.

Application filed April 6, 1922. Serial No. 550,068.

To all whom it may concern:

Be it known that I, ARCHILLES A. BARTON, a citizen of the United States, residing at Los Angeles, in the county of Los Angeles, State of California, have invented a new and useful Improvement in Pump Pistons, of which the following is a specification.

My invention relates to pumps and more particularly to pistons used in such pumps.

It is particularly applicable to a deep well pump of the duplex or triplex variety. The term "deep well pump" as used by me denotes a pump having a pump barrel which is carried at the end of a string of pipe and which is submerged in the water of the well at some distance below the surface. The terms "duplex" and "triplex" as used by me denote pumps in which two or more pistons are used, one working vertically above the other, all being operated by a single pump head located above the surface of the well.

While my invention is particularly applicable to duplex and triplex deep well pumps, and while it has a special utility and novelty when so applied, nevertheless I do not wish to be understood as restricting myself to such an application of my invention which should be limited only by the annexed claims.

An object of my invention is to provide a piston of this character which will have a very large opening therethrough, thus cutting down the water frictions through the buckets and valves and increasing the efficiency.

A further object of my invention is to provide a valve for use in such a piston which will have a single closing surface and which will be flexibly guided so that it makes a tight closure with that surface at all times.

A still further object of my invention is to provide a valve having a packed central opening and to provide means for preventing undue wear on the packing about said central opening.

Further objects and advantages will be made evident hereinafter.

Referring to the drawing, which is for illustrative purposes only,

Fig. 1 is an elevation partly in section of an upper or intermediate bucket used in a deep well pump, which bucket employs one embodiment of my invention.

Fig. 2 is an enlarged central section through the valve used in my invention.

Fig. 3 is a section on a plane indicated by the line 3—3 of Fig. 1, and

Fig. 4 is a section on a plane indicated by the line 4—4 of Fig. 1.

In the form of the invention illustrated a single bucket is shown, this bucket operating inside the pump barrel 11 and consisting of a body 12 carried by three arms 13 from a hub 14. The body carries cup leathers 15 which are held in place by spacers 16, members 15 and 16 being clamped solidly by a nut 17. The hub 14 is threaded at 18 to receive the lower end of a pump rod 20, this pump rod consisting of a hollow tube which extends upwardly to the top of the well and is operated by a pump head, not shown. Passing through a central opening 21 in the hub 18 is a second pump rod 22 which may be a hollow pipe or a solid rod as shown. This pump rod 22 extends downwardly inside the pump barrel 11 and is connected to the next lower bucket of the pump which is not shown. The pump rods 20 and 22 are so reciprocated that one of them is moving upwardly at certain times when the other is moving downwardly, this being necessary to provide a continuous flow of water, one of the buckets lifting when the other bucket is falling. The bucket 11 is provided with a central passage 25 which terminates at its top in a valve seat 26. The valve seat 26 is preferably conical or spherical in contour and it is closed by a valve 30 which has a surface 31 machined to fit accurately against the seat 26.

For the purpose of guiding the bucket, I provide a short tube 35 which is secured in the hub 14 by threads 36. The tube 35 extends downwardly and through the center of the valve 30. For the purpose of making a tight closure around the member 35, I provide cup leathers 40 and 41 which are spaced apart by a member 42 and are clamped in place by means of a nut 43. The cup leathers 40 and 41 serve two purposes; in the first place, they make a tight closure around the member 35, thus preventing water from passing downwardly around the member 35 when the valve 30 is seated; they also serve another highly important purpose in that they tend to guide the valve 30 in a straight line so that it makes a tight closure all around on the seat 26, this closure,

however, being a flexible one so that the valve 30 has a good opportunity to find its own seat and to adjust itself laterally to provide a perfect seat at all times.

5 For the purpose of assisting in a rapid closing and secure seating of the valve, I provide a compression spring 50 which presses against a collar 51 formed on the hub 14 and is seated against a shoulder 52 in 10 the valve 30. Since the member 35 is secured in the hub 14, it moves with the hub and the only movement between it and the valve 30 is that due to the lifting and seating of the valve on the seat 26. The pump rod 22 fits loosely in the member 35 which is 15 preferably formed of brass or bronze and since this fit is a loose one, there is very little wear on the rod 22 or on the member 35.

I claim as my invention:

20 1. In a pump, the combination of: a bucket having a central passage therethrough; a pump rod extending through said passage for the purpose of operating a lower bucket in said pump; a hub above said 25 passage, said hub having a central hole through which said pump rod extends; a valve seating in said passage, said valve also having a central orifice through which said pump rod also extends; a tube secured in 30 water tight relation in said central hole in said hub and extending downwardly from

said hub, said pump rod extending through the center of said tube which extends through the central orifice of said valve; packing means making a tight closure in said central orifice about said tube; and means connecting said bucket with said hub.

2. In a pump, the combination of: a bucket having a central passage therethrough; a pump rod extending through said 40 passage for the purpose of operating a lower bucket in said pump; a hub above said passage, said hub having a central hole through which said pump rod extends; a valve seating in said passage, said valve 45 also having a central orifice through which said pump rod also extends; a compression spring between said hub and said valve so disposed that it tends to seat said valve in said central passage; a tube secured in water 50 tight relation in said central hole in said hub and extending downwardly from said hub, said pump rod extending through the center of said tube which extends through the central orifice of said valve; packing means making a tight closure in said central orifice about said tube; and means connecting said bucket with said hub.

In testimony whereof, I have hereunto set my hand at Los Angeles, California, this 29th day of March, 1922.

ARCHILLES A. BARTON.
